[57] **CLAIM**

The ornamental design for the office workspace with shared corridor, as shown and described.

DESCRIPTION

FIG. 1 is a front isometric view of an office workspace with shared corridor provided in accordance with a first embodiment of the present invention;

FIG. 2 is a front elevational view thereof;

FIG. 3 is a left side elevational view thereof, the right side elevational view being identical;

FIG. 4 is a rear elevational view thereof;

FIG. 5 is a top plan view thereof;

FIG. 6 is a bottom plan view thereof;

FIG. 7 is a front isometric view of an office workspace with shared corridor provided in accordance with a second embodiment of the present invention;

FIG. 8 is a front elevational view thereof;

FIG. 9 is a left side elevational view thereof, the right side elevational view being identical; and,

FIG. 10 is a rear elevational view thereof, the top plan and bottom plan views thereof being identical to FIGS. 5 and 6, respectively.
